US0D1071853S

(12) **United States Design Patent** (10) **Patent No.:** **US D1,071,853 S**
(45) **Date of Patent:** **** Apr. 22, 2025**

(54) **CHARGING STATION FOR CLEANING ROBOT**

(71) Applicant: **Dreame Innovation Technology (Suzhou) Co., Ltd.**, Suzhou (CN)

(72) Inventors: **Zhenjiang Hu**, Jiangsu (CN); **Xiaoye Xie**, Jiangsu (CN); **Chunyang Dou**, Jiangsu (CN); **Nan Jiang**, Jiangsu (CN); **Yan Zhang**, Jiangsu (CN); **Wenbin Shen**, Jiangsu (CN)

(73) Assignee: **Dreame Innovation Technology (Suzhou) Co., Ltd.**, Suzhou (CN)

(**) Term: **15 Years**

(21) Appl. No.: **35/517,859**

(22) Filed: **Nov. 28, 2022**

(80) **Hague Agreement Data**

Int. Filing Date: **Nov. 28, 2022**

Int. Reg. No.: **DM/230194**

Int. Reg. Date: **Nov. 28, 2022**

Int. Reg. Pub. Date: **Jul. 21, 2023**

(30) **Foreign Application Priority Data**

Jun. 21, 2022 (CN) 202230381541.9

(57) **CLAIM**

The ornamental design for a charging station for cleaning robot as shown and described.

DESCRIPTION

1. Charging station for cleaning robot

1.1: Perspective

1.2: Front

1.3: Back

1.4: Top

1.5: Bottom

1.6: Left

1.7: Right

The broken lines in the reproductions are for the purpose of illustrating portions of the charging station for cleaning robot which form no part of the claimed design.

1 Claim, 7 Drawing Sheets
